UNITED STATES PATENT OFFICE.

JOHN E. CONZELMAN, OF WEBSTER GROVES, MISSOURI, ASSIGNOR TO UNIT CONSTRUCTION COMPANY, OF ST. LOUIS, MISSOURI, A CORPORATION OF DELAWARE.

WALL CONSTRUCTION.

1,114,584.

Specification of Letters Patent. Patented Oct. 20, 1914.

Original application filed November 9, 1911, Serial No. 659,298. Divided and this application filed August 7, 1912. Serial No. 713,900.

To all whom it may concern:

Be it known that I, JOHN E. CONZELMAN, a citizen of the United States, residing at the city of Webster Groves, in the county of 5 St. Louis and State of Missouri, have invented certain new and useful Improvements in Wall Construction, (Case A,) of which the following is a specification.

This application is a division and continuation of one filed by me November 9, 10 1911, Serial No. 659,298.

This invention relates to concrete building structures, and has for its object to provide a structure in which concrete slabs and 15 columns are united to form a wall having an air-space therein and being particularly adapted for cold storage plants, residences, and the like.

With this object in view, the present invention consists of the novel features of construction and arrangement of parts, as will be hereinafter more fully described and pointed out in the claim.

In the accompanying drawings forming 25 part of this specification, in which like numbers of reference denote like parts wherever they occur, Figure 1 is a side elevation of part of a wall embodying this invention and including two columns and wall slabs connected therewith; Fig. 2 is a sectional view on the line 2—2, Fig. 1; Fig. 3 is a sectional view on the line 3—3, Fig. 1; and Fig. 4 is a fragmentary perspective view of the form 30 of slab used in this construction.

Each panel of the wall consists of a pair 35 of columns or uprights 1 and a plurality of vertically-disposed slabs 2, the ends of which fit in grooves 3 in the sides of said columns. Each slab 2 is preferably formed with a 40 rectangular configuration, and has a hollow tile 4 or a plurality of such tiles embedded therein, so as to afford an air-space in same. Said tiles 4 extend vertically in the slab 2 and the upper ends thereof project above 45 the top of said slab, an opening or groove 5 being left below the lower ends of said tiles in the bottom of said slab. By this arrangement, when the slabs 2 are placed one on top of another between the columns 1, the ends 50 of said slabs fit in the grooves 3 in said columns, as best seen in Fig. 3, and the upper ends of the tiles 4 in each slab 2 fit in the

opening or groove 5 in the bottom of the next slab 2 above same, so that the tiles 4 in said slabs register substantially in vertical 55 alinement.

The columns 1 are preferably supported on a foundation 6, which extends underneath the lower slabs in each panel, and a rib 7 on said foundation fits in the opening 60 or groove 5 in the bottom of the lower slab 2. If desired, the adjoining edges of each two adjacent slabs 2 and the ends of said slabs may be "buttered" with grout just 65 previous to the placing of said slabs in position in the wall, so that when said grout sets, said slabs are united integrally and said columns and said slabs are, also, united integrally, thus constituting a monolithic 70 structure. The bottoms of the lower slabs 2 of each panel may, also, be "buttered" with grout, which, when set, unites the lower slabs and foundation integrally.

It will be readily understood that a wall 75 constructed with slabs having tiles embedded therein, to afford an air-space within said wall is light in weight and renders the space or room inclosed thereby moisture proof. By reason of the tiles 4 being arranged to project above the top of each slab and, also, 80 to leave an opening or groove 5 in the bottom of said slab so that the slabs can be united by tongue-and-groove joints, the junctures are thereby made secure and durable. Furthermore, the slabs and columns 85 coöperate and are interengaged to form a rigid, secure and lasting structure.

I claim:

In concrete slab construction, a series of 90 superimposed slabs, each slab consisting of a concrete body of rectangular cross section having a series of transverse similar hollow tiles embedded therein, each tile being of 95 rectangular cross-section and having their sides arranged in contacting engagement throughout, one of the ends of each of the tiles extending beyond one side of the body to form a single tongue of rectangular cross section having straight uninterrupted sides and a straight uninterrupted top face, the 100 opposite ends of the tiles being disposed in spaced relation to the opposite side of the body whereby to provide a single opening at said opposite end of the body, which

opening has substantially the same rectangular cross-section as that of the tongue and has a straight uninterrupted bottom face formed by said opposite ends of the tiles, whereby when the tongue of a slab projects into the opening of an adjacent slab the top face of the tongue will directly seat on the adjacent ends of the tiles in an adjacent slab,

and whereby the openings of the tiles will register.

In testimony whereof I hereunto affix my signature in the presence of two witnesses.

JOHN E. CONZELMAN.
